U.S. Cl. D8—22

FIG. 1 is a left side elevation view of a tube fitting wrench showing the present design, the right side elevation view being identical thereto and opposite hand;

FIG. 2 is a top plan view of the tube fitting wrench of FIG. 1;

FIG. 3 is a bottom plan view of the tube fitting wrench of FIG. 1;

FIG. 4 is a front end elevation view of the tube fitting wrench as viewed from the left in FIG. 1;

FIG. 5 is a rear end elevation view of the tube fitting wrench as viewed from the right in FIG. 1; and

FIG. 6 is a cross-sectional view taken along line 6—6 of FIG. 2.

The broken line representation of a hexagonal nut in FIG. 1 is included for purposes of illustration only.

I claim:

The ornamental design for a tube fitting wrench, substantially as shown and described.
